SPARK ARRESTER

Charles A. Soley, Chicago, Ill., assignor to Locomotive Firebox Company, Chicago, Ill., a corporation of Delaware

Application May 12, 1933, Serial No. 670,684

10 Claims. (Cl. 110—122)

This invention relates to improvements in spark arresters and it consists of the matters hereinafter described and more particularly pointed out in the appended claims.

6 The spark arresters with which my invention is more particularly concerned are those disposed in the smoke box of the locomotive and operate with a centrifugal or so-called cyclonic action whereby the products of combustion entering the same are caused to take on a whirling action in a circular path. By reason of this action, the heavier live sparks and cinders bombard the inner face of the arrester casing and are broken up into particles of reduced dimensions and weight. These particles enter the effective zone of draft about the bottom of the stack extension to be entrained therein for discharge out through the stack in a harmless condition.

20 Spark arresters of this kind as heretofore made have certain structural deficiencies which the present invention seeks to overcome.

In such arresters, it is apparent that due to the character of the products of combustion entering the same, their bombardment of the inner surface of the casing, sets up a severe abrasive action which soon wears holes in the casing. Such holes materially reduce the operating efficiency of the arrester.

30 In some arresters of this kind, the upright walls thereof are made in separate sections. This leaves minute cracks or crevices between the abutting edges of the sections and such cracks or crevices are usually covered only by metallic straps. It is apparent that with such straps it is difficult to prevent leakage into the casing under the draft action existing therein.

One of the objects of the present invention is to provide a spark arrester of this kind which has an interior liner of greater wear resisting qualities, whereby a longer period of usefulness, without frequent servicing is possible.

Another object of the invention is to provide in an arrester of this kind, wear resisting liners which may be readily replaced when worn. Said liners may or may not include breaker strips forming elongated shoulders against which cinders and sparks engage to be more quickly broken up or disintegrated into harmless particles for entrainment into and discharge up and out of the stack.

A further object of the invention is to provide a simple and effective seal at the joints between the several sections whereby leakage into the arrester casing is prevented.

The above mentioned objects of the invention as well as others, together with the several advantages thereof, will more fully appear as I proceed with my specification.

In the drawings:

Fig. 1 is a longitudinal vertical sectional view through the front end of a locomotive boiler provided with a spark arrester embodying the preferred form of the invention;

Fig. 2 is a horizontal sectional view through the same as taken on the line 2—2 of Fig. 1;

Fig. 3 is a transverse vertical sectional view through the front end of the smoke box shell of the boiler as taken on the line 3—3 of Fig. 1;

Fig. 4 is a detail horizontal sectional view on an enlarged scale through a part of the arrester as taken on the line 4—4 of Fig. 3;

Fig. 5 is a detail vertical sectional view on an enlarged scale through a part of the arrester as taken on the line 5—5 of Fig. 3;

Fig. 6 is another detail vertical sectional view on an enlarged scale as taken in the plane indicated by the line 6—6 of Fig. 3 and shows more particularly the key bolted connection between the flange on the top of the casing and the top portion of one of the upright sections of the casing;

Fig. 7 is a view in elevation of a part of the flange of the top wall of the casing and illustrates more particularly the shape of the holes therein for receiving the key bolts carried by the top end of the associated upright sections;

Fig. 8 is a view in elevation of the inner face of one of the upright wall sections of the casing, and illustrates more particularly one arrangement of the breaker strips on the liner;

Fig. 9 is a view similar to Fig. 8 and shows a different form of arrangement for the breaker strips on the liner;

Fig. 10 is a horizontal sectional view through the casing section shown in Fig. 8, the plane of the section being taken on the line 10—10 of Fig. 8, and

Figs. 11, 12, 13 and 14 are views similar to Fig. 10 through casing sections having modified forms of breaker strip arrangements, as will be more fully described later.

In general, my improved spark arrester comprises a casing arranged in the smoke box of the boiler and so disposed with respect to the stack extension and exhaust nozzle that both open thereinto to provide the necessary draft action. The casing in this instance has its inlet opening at the rear so as to face the adjacent flue sheet but this arrangement of said opening

110

is not essential to the real spirit of the invention. Associated with said inlet opening is a baffle which blocks off all space of the smoke box forward of the inlet.

5 The casing includes top and bottom walls with marginal flanges that face each other and these walls have suitable openings to receive the stack extension and nozzle respectively. The casing also includes upright, straight side walls and an 10 upright semicircular front end wall that merges into both side walls.

These upright walls are made up in sections suitably secured at their top and bottom ends by means of key bolts to the flanges of the top and 15 bottom walls. The adjoining edges of the sections are overlapped on the outside of the casing by suitable straps, a sealing strip of a softer material being arranged between said adjoining edges and straps to insure against leakage into 20 the casing at these points.

On the inside of each section is a liner which is highly resistant to wear under the abrasive action of sparks and cinders in their whirling movement in the casing under draft action.

25 The liners of the various sections are furthermore formed with inward projections or breakers in the form of metallic strips. In the whirling action that the sparks and cinders take on while in the casing, the sparks and cinders engage the breaker strips and this breaks them into smaller particles in much less time than heretofore so that the particles are more easily entrained for discharge up the stack as harmless material incapable of starting wayside fires. By 30 35 reason of the disintegrating action, the cinders and sparks are more quickly discharged up the stack. Therefore their abrasive action is reduced to a minimum and wear on the liners is reduced in proportion.

40 Referring now in detail to that embodiment of the invention, illustrated in the accompanying drawings:

1 indicates as a whole the tubular body of the smoke box shell that is operatively connected 45 at its rear end to the front end of the boiler shell 2 in any suitable manner, the front end of the smoke box shell being normally closed by an associated front end and door (not shown).

50 3 indicates the front flue sheet of the boiler in which the associated ends of the usual tubes or flues are secured, so as to deliver the products of combustion into the smoke box. 4 indicates the barrel of the stack having a flanged base 55 secured to the body of the smoke box shell about the usual opening therein. Welded in said opening is a ring 5 through which a top end part 6a of a stack extension 6 projects. This part of the extension is welded in the ring 60 and its top extremity extends a suitable distance up into the stack barrel. The bottom extremity of the bottom part 6b of the stack extension is flared as at 7.

The exhaust stand or pipe is indicated at 8. 65 This stand or pipe rises from the bottom of the smoke box shell in line with the stack and is provided at its top end with one or more discharge tips 9.

In the smoke box shell is located a cyclonic 70 separator casing 10 which comprises flat top and bottom walls 11 and 12 respectively, upright side walls 13-13 and a semicircular front wall 14, the casing being open at the rear end to provide an inlet therefor that faces the flue sheet 75 3. This casing rests upon front and rear, trans-

versely extending angle bar supports 15 so that its bottom wall is substantially flush with the top of the nozzle stand 8, there being a suitable hole in said bottom wall for the nozzle tips. On 80 said bottom wall about said nozzle tips is provided an upright cinder ring 16. The open rear inlet end extends through a vertical baffle 17 arranged in the plane of the front end of the boiler shell 2. This baffle blocks off all of the smoke box to the front of the inlet opening for 85 the casing.

The top and bottom walls of the casing are provided with marginal flanges 18 and 19 respectively which face toward each other. In 90 said flanges are suitable openings through which certain key bolts extend for a purpose soon to appear, said openings in the rounded front end part of said flanges being elongated horizontally as at 20 in Fig. 7.

The stack extension 6 passes up through a 95 suitable opening in the top wall of the casing and is provided with an angle bar ring 21 that rests upon said top wall. At a point below said ring, and arranged within the casing the bottom part 6b of said extension carries angle 100 brackets 22. Bolts 23 extend through said brackets, the top wall and the angle bar ring respectively, whereby the associated parts are rigidly connected together. The stack extension parts 6a-6b meet in the plane of the 105 upright flange of the ring 21 and the use of such parts make assembly of the arrester an easy matter.

The upright side walls and the semicircular front wall of the casing are made up in sections 110 A, B, C, D, E and F respectively, as best indicated in Fig. 2. The sections A and F make up the side walls 13 and the remaining sections make up the rounded or semicircular front wall. All of these sections, which are of a height approximating the distance between the top and bottom walls, fit at their top and bottom margins against the inside of the flanges 18 and 19 thereof, respectively.

115 In the inlet for the casing are provided laterally spaced deflectors 24, 25 and 26 respectively arranged to direct the incoming products of combustion toward the section F of the casing. Associated with the section A of the casing is an upright segmental wall 27 curved to form 120 a continuation of the rounded front wall of the casing. The segmental wall which extends from the top to the bottom of the casing includes an angular deflector wing 28 disposed parallel with the deflectors 24, 25 and 26 respectively. 125 130

The various sections A to F inclusive, each 135 comprise a suitably formed sheet 29 that carries at its top and bottom margins and along each side margin, outwardly extending key bolts 30 and 31 respectively. Preferably the tapered head of said bolts are set in suitably tapered recesses so that the tops of said heads are flush with the inner surface of the sheet. If desired these bolts may be permanently fixed in the sheet.

140 Associated with the abutting side edges of adjacent sections and on the outside thereof are butt straps 32 that overlap a marginal part of said adjacent sections. These straps carry on their inner surface along their median line 145 a sealing strip 33 such as an asbestos tape. This strip is provided on its outer surface with a cementitious coating so that it will adhere to the associated butt strap and is provided on its inner surface that engages the margins of 150

adjacent sections, with a graphite coating so that it will not adhere to said margins when compressed there against as will soon appear.

Similar sealing strips 34-35 are applied to 5 the outer faces of the top and bottom margins of said sections, there being suitable holes in said strips to accommodate the bolts 30-31.

All parts of the casing except the section C are assembled outside the smoke box. In applying the section A or F to the top and bottom walls 11 and 12, its key bolts 30 are passed through the openings 20 in the flanges 18 and 19 and then a washer 30a is applied to the outer end of each bolt. Thereafter a wedge key 15 30b is driven through the slot in each bolt. This draws the section into place with a tightly sealed top and bottom engagement with the flanges 18 and 19. The curved sections B, D and E are then applied in the same manner, after 20 which a butt strap 32 (with its sealing strips 33 thereon) is applied to overlap the adjacent margins of each two adjacent sections, the butt straps having holes to accommodate the key bolts 31. Thereafter washers 31a are applied 25 to the bolts up against the butt straps and wedge keys 31b are driven through the slots in said bolts. This draws the butt straps in toward the margins of said sections and acts to compress the sealing strips to tightly close and 30 seal the seams or crevices between the edges of said sections.

As the sections are all moved into place in a straight line, it is apparent that with the bolts extending radially with respect to the curved 35 sections, it would be impossible to get the bolts to pass through round holes in the flanges 18 and 19. By elongating them as shown at 20 in Fig. 7, leeway is provided for such movement, the holes being closed by the sealing strips 34, 40 35 when the casing is assembled all but the section C.

The thus far assembled casing is now moved through open front end of the smoke box shell into position upon the supports 15 with its inlet 45 end extending through the baffle 17. The workman from within the thus far assembled casing, then applies the stack extension parts 6a-6b and the bolts 23.

As before stated, the section C is the last one 50 to be assembled in place and bears the handle 36. After all other work has been completed in the casing, the workman steps out of the opening left to receive the section C and works the section around into position. When positioned, by pulling on the handle 36, the bolts 30 of said section will pass through the openings 20 in the flanges 18 and 19. Thereafter washers 30a and wedge keys 30b are applied and this 55 draws the section into place. The butt straps 32 are applied and washers 31a and wedge keys 31b are applied to the bolts 31a and the assembly is completed.

Each section B, C, D, E and F is provided on 60 its inner face with a liner sheet 37 of high wear 65 resisting characteristics and on the inner face of each liner are provided means which interrupt the smooth continuity of the face as provided by the liners of the various sections.

This means may be formed in several different ways. In Figs. 8 and 10 this means is 70 shown in the form of upright parallel breaker strips 38. These strips are welded in place at suitable spaced distances apart as at 39 and when worn beyond usefulness, may be removed 75 and replaced by new ones. It is to be noted that

the breaker strips are so disposed on the liner that one strip is located along one margin of the section and a breaker strip is spaced within the other margin. Thus, when all the sections are operatively positioned the breaker strips on all the sections are spaced equal distances apart. 80

Instead of arranging the breaker strips vertically as shown in Fig. 8, they may be arranged obliquely as shown at 38a in Fig. 9. The purpose of such disposition is to tend to throw the sparks upwardly and hence to prevent their falling to the bottom of the spark arrester casing. In both instances, the breaker strips are of a flat cross section but this cross section is not absolutely essential because they may be made of a semicylindrical cross section as at 38b in Fig. 11. In Fig. 11, only the liner and breaker strips are shown. 85

In Fig. 12, I have shown a breaker strip 37a that is corrugated when considered in horizontal 90 section. This arrangement provides hills and valleys, the hills acting as the breaker strips. 95

In Fig. 13, I have shown a heavy wire netting 37b secured to the inner face of the liner 37 and in Fig. 14, this netting is shown as laterally 100 spaced strips of netting 37c.

In the operation of the arrester, with the nozzles discharging into the stack, a strong draft action is set up in the casing. The products of combustion leaving the tubes or flues enter the 105 inlet of the casing and by reason of the deflectors, are directed toward the sections F and E of the casing and then take on a whirling action in a circular path. In this action, or movement, the heavier cinders and sparks 110 engage the breaker elements and are gradually broken into smaller particles. These smaller particles are drawn toward the center of the casing to be entrained into the stack for discharge. Those particles which still maintain 115 sufficient mass to keep them outside the influence of the entraining action, are thrown against and bounce off of other breaker strips until reduced to particles of such size as to be entrained for discharge up the stack. 120

The cinders and sparks in their whirling movement in a circular path have a highly abrasive action which is materially resisted by the liners but eventually holes will appear therein. When such a condition arises the wedge keys of the 125 bolts of the section C are withdrawn and the whole section is moved inwardly of the casing to leave an opening through which a workman may enter.

By working from both the inside and outside 130 of the casing the various sections may be taken out of the casing. The worn liners and breaker bars or strips are then removed and others applied in their stead. Thereafter the sections are replaced. In this manner, the life of the arrester 135 is materially increased and due to the breaker strips, the cinders are more quickly broken up and entrained into the draft stream for discharge upwardly and out of the stack.

While in describing the invention, I have referred in detail to the form, arrangement and construction of the various parts of the arrester, the same is to be considered only in its illustrative sense so that I do not wish to be limited thereto except as may be specifically set forth 145 in the appended claims.

I claim as my invention:

1. In a spark arrester, an arrester casing having an inlet opening and made up of a plurality of casing sections, means overlapping 150

- marginal portions of adjacent sections, sealing means between said marginal portions of adjacent sections and said overlapping means, and means for drawing said marginal portions and 5 said overlapping means together for compressing the sealing means between them and there provide a leakage tight joint between said sections.
2. In a spark arrester, an arrester casing having an inlet opening and made up of a plurality 10 of casing sections, a butt strap overlapping marginal portions of the outer surface of adjacent sections, a sealing strip between said marginal portions of adjacent sections and said butt strap, and means associated with said marginal portions 15 and said butt strap for drawing them together for compressing the sealing means between them and there provide a leakage tight joint between said sections.
3. In a spark arrester, an arrester casing having an inlet opening and made up of a plurality 20 of casing sections, a butt strap overlapping marginal portions of the outer surface of adjacent sections, a sealing strip adhered to the inner surface of said strap and having its other 25 surface engaged with said marginal portions and treated so as not to adhere thereto, and means associated with said marginal portions and butt strap for drawing them together so as to compress said sealing strip between them and there 30 provide a leakage tight joint between said sections.
4. In a spark arrester, an arrester casing having an inlet opening and made up of a plurality of casing sections, bolts carried by marginal 35 portions of adjacent sections to extend outwardly therefrom, a butt strap overlapping said marginal portions and having openings through which said bolts extend, a sealing strip between said butt strap and overlapping margins, and 40 means associated with said bolts for drawing said margins and butt straps together for compressing the sealing strip to provide a leakage tight joint between said adjacent sections.
5. In a spark arrester, an arrester casing having an inlet opening and made up of a plurality 45 of casing sections, and top and bottom walls having marginal flanges, a compressible sealing member between the top and bottom margins of said sections and said flanges, means 50 passing through said margins and flanges for drawing them together to compress the sealing members into a leakage tight joint, a butt strap overlapping upright margins of adjacent sections, a sealing strip between said upright margins of said sections and said butt strap, and 55 means associated with said upright margins and butt straps respectively for drawing them together so as to compress said sealing strip to there provide a leakage tight joint.
6. In combination with a locomotive smoke 60 box shell and associated stack and exhaust nozzle, a centrifugal spark arrester casing in said shell having an inlet and a substantially annular side wall, means in said inlet for directing the incoming products of combustion toward one side of the casing to there take on a whirling path about the inside of the casing, and a wear resisting liner following about the inner surface of at least a part of said wall. 80
7. In combination with a locomotive smoke box shell and associated stack and exhaust nozzle, a centrifugal spark arrester casing in said shell having an inlet and embodying therein a plurality of wall sections assembled into annular wall form, means providing a liner following about the inside of certain of said wall sections, means in said inlet for directing the incoming products of combustion toward one side of the casing against the liner to there take on a whirling path, and means for securing the adjacent margins of the casing sections together 85 90 and including sealing means. 95
8. In combination with a locomotive smoke box shell and associated stack and exhaust nozzle, an arrester casing in said shell having an inlet, means in said inlet for directing the incoming products of combustion toward one side of the casing to there take on a whirling path about the inside of the casing, a wear resisting liner on the inside of said casing, and means on the inner surface of said liner adapted to be engaged by said products of combustion while in motion in said path for breaking them into smaller particles for entrainment into the stack for discharge. 100
9. In combination with a locomotive smoke box shell and associated stack and exhaust nozzle, an arrester casing in said shell having an inlet, means in said inlet for directing the incoming products of combustion toward one side of the casing to there take a whirling path about the inside of the casing, a wear resisting liner on the inside of said casing, and breaker strips on the inside of the liner adapted to be engaged by said products of combustion while in motion in said path for breaking them up into smaller 105 particles for entrainment into the stack for discharge. 110
10. In combination with a locomotive smoke box shell and associated stack and exhaust nozzle, an arrester casing in said shell having an inlet and embodying therein a plurality of upright wall sections, liners carried on the inside of certain of said sections, means associated with margins of adjacent sections to provide a sealed joint between them, means in said inlet 115 for directing the incoming products of combustion toward one side of the casing to there take on a whirling action in a circular path and spark and cinder breaking means on certain of said liners on said sections. 120 125 130
